UNITED STATES PATENT OFFICE.

JETHRO J. RICE, OF GRAND RAPIDS, MICHIGAN.

DESIGN FOR A CHIFFONIER, &c.

SPECIFICATION forming part of Design No. 23,927, dated January 1, 1895.

Application filed September 17, 1894. Serial No. 523,281. Term of patent 7 years.

To all whom it may concern:

Be it known that I, JETHRO J. RICE, a citizen of the United States, residing at Grand Rapids, in the county of Kent and State of Michigan, have invented and produced a new and original Design for Chiffoniers and Analogous Articles of Furniture, of which the following is a specification, reference being made to the accompanying drawing, in which the figure is a perspective view.

The leading feature of my design consists in a chiffonier or analogous article of furniture the side ends of the body of which are each formed with or in a compound curve extending from the base to the top of said body.

In the drawing in which the design is illustrated in a chiffonier the numeral 1, indicates

a chiffonier body, the side ends of which are formed with or in a compound curve extending from the base to the top of said body. The curve of the ends is as shown, a compound one consisting of upper and lower concaved portions 3 and 4 and an intermediate convex portion 5. Ornamental ridges 6 and 7, are arranged at the front and rear of the curved ends and terminate in legs 8.

What I claim is—

The design for a chiffonier or analogous article of furniture herein shown and described.

In witness whereof I have hereunto set my hand and seal in the presence of two witnesses.

JETHRO J. RICE. [L. S.]
